CENTRIFUGE APPARATUS

Edward G. Pickels, Palo Alto, Calif., assignor to
 Specialized Instruments Corporation, Belmont,
 Calif., a corporation of California

Application May 9, 1950, Serial No. 160,888

1 Claim. (Cl. 233—24)

1

This invention relates generally to centrifuge apparatus, and particularly to ultra centrifuges which utilize high rotative speeds of the order of from 5,000 to 40,000 R. P. M. or more.

Because of the high rotative speeds employed in ultra centrifuge equipment it is not possible to design the rotors with a factor of safety as high as might normally be considered good engineering practice, and therefore it is necessary to guard against excessive rotative speeds. For example if a rotor is designed to operate at a maximum speed of 20,000 R. P. M., excessive speed of the order of 30,000 R. P. M. may cause bursting of the rotor, with resulting damage to other parts of the equipment, and possible injury to the attendant.

Ultra centrifuges are generally intended for laboratory use, and the rotor drive is arranged to make available any one of many possible speeds of rotation, and to govern or regulate the speed to that selected. Several sizes and types of rotors are generally supplied to accommodate for various types of work and different rotative speeds. Thus one rotor may be adapted for one type of separating work and designed for speeds ranging up to 20,000 R. P. M., and another designed for higher speeds which may for example range up to 40,000 R. P. M. There is always the possibility that an attendant may apply the wrong rotor for the speed of operation selected, with the result that the safe speed of operation for a particular rotor is exceeded. In addition the electrical speed control means employed may fail to function properly and thereby cause the rotor to be driven at an excessive speed.

It is a general object of the present invention to provide improved centrifuge apparatus having means whereby when the safe speed of operation of a rotor is exceeded, the driving torque to the rotor is interrupted.

Another object of the invention is to provide improved means of the above character which is relatively simple in construction, and which is operated responsive to the magnitude of centrifugal force applied to a member carried by the rotor.

Another object of the invention is to provide a simplified assembly unit adapted to be mounted directly upon a centrifuge rotor, and which will cause a member to be automatically extended in a radial direction to perform a safety control operation, when the speed of the rotor exceeds a predetermined value.

Additional objects and features of the invention will appear from the following description

2

in which the preferred embodiment of the invention has been set forth in detail in conjunction with the accompanying drawing.

Referring to the drawing—

Figure 1 is a side elevational view in section, illustrating centrifuge apparatus incorporating the present invention.

Figure 2 is a cross-sectional detail taken along the line 2—2 of Figure 1.

Figure 3 is a cross-sectional detail on an enlarged scale taken along the line 3—3 of Figure 1.

Figure 4 is a schematic view illustrating circuit means for the driving motor.

The apparatus illustrated in Figure 1 includes a centrifuge rotor 10 having sample receiving pockets 11. A vertically extending stud shaft 12 is carried by the journal mounting 13, and is adapted to be driven by an electric motor, through suitable gearing. The lower end of the rotor has a socket opening 14 which accommodates the upper end of the shaft 12. The shaft also carries an eccentric driving pin 16, adapted to extend into driving relation with a pin 17 which is fixed to the rotor. The rotor may be enclosed within the refrigerated liner of a suitable vacuum chamber, the top of which is removable to facilitate access. The lower wall 18 of the liner can be secured to the lower wall 19 of the vacuum chamber by the collar 21. A vacuum sealing member 22, formed of rubber or like resilient material, extends between wall 19 and the journal mounting 13, and is expanded by compression spring 23 to hold its end faces in sealing engagement with the cooperating metal surfaces. The driving motor and gearing are carried by cushion mounting means whereby the shaft 12 is permitted a substantial amount of lateral displacement. This makes possible self-balancing action of the rotor.

The safety control means which I employ makes use of a centrifugally operated unit 24, which is removably mounted in the lower portion of the rotor body. This unit (see Figure 3) includes a fitting 26, which is externally threaded for engaging the threaded bore 27 in the rotor body. A pin 28 is slidably disposed in the fitting 26, and is stepped to provide the annular shoulder 29. The bore 31 which accommodates the pin is likewise of stepped diameter to provide a shoulder 32, which is engaged by shoulder 29 when the pin is projected.

A shear pin 33 serves to normally lock the pin 28 in retracted position within the fitting 26. Pin 33 extends through registering openings in

the pin and fitting, as illustrated in Figure 3. When the pin 28 is forced outwardly with sufficient centrifugal force, shear forces are applied to the pin 33 at two points. The shear strength of the pin 33 is selected so that for a predetermined outward force applied to pin 28, the pin 33 will shear to permit pin 28 to move to the projected position illustrated in dotted lines in Figure 3. It will be evident that the unit 24 is readily removable for replacement of a sheared pin 33.

Adjacent to the path of movement of the unit 24, there is an electrical conductor 36 (Figure 1) in the form of a vertically extending wire or knock-out pin. The upper end of the pin 36 is shown pressing against a spring metal strip 37. This strip is bent to extend inwardly beneath the annular plate 38, for electrical connection with the upper end of the terminal bolt 39. The lower end of pin 36 is attached to the upper end of a bolt 41, which in turn is electrically connected by strip 42 with the terminal bolt 43. The lower ends of the terminal bolts 39 and 43 are available for electrical connection to a circuit serving to control energization of the driving motor. As illustrated in Figure 3, pin 36 is disposed in the path of movement of the pin 28, when the pin is in its extended limiting position illustrated in dotted lines. Therefore it will be evident that when pin 28 is extended during high speed operation of the rotor, it immediately strikes and breaks or knocks out the conductor pin 36.

The actual connections between the knock-out pin 36 and the driving motor can vary in practice, but should be such that breakage of the pin either discontinues current supply to the motor in entirety, or modifies operation of the motor or drive through the speed control means employed to reduce the driving torque and the speed of operation. One suitable arrangement is illustrated schematically in Figure 4. In this instance the variable speed electric driving motor 48 is shown driving the rotor 46 through the speed multiplying gearing 47. The customary magnetic starter box 43 connects between the motor and the current supply lines 49. The starting box 43 has a control circuit 51 which when opened, causes the motor 48 to be de-energized. The conductor 36 is connected in series with the circuit 51, so that when the conductor 36 is broken, the circuit is opened to de-energize the motor 48.

It will be evident that my apparatus provides positive means to protect ultra centrifuge rotors from being subjected to excessive speeds of rotation. The unit 24 can be factory installed in the rotor and constructed to provide protection against excessive speeds for that particular piece of equipment. Therefore when several different rotors are being used with the same equipment, but designed for different speeds of rotation, protection is automatically provided in accord-

ance with the rotor design. The protection is positive and dependable in its action and it can be made to operate within relatively close limits. After the prescribed speed of operation has been exceeded and pin 28 has been projected to interrupt driving of the motor, it is a relatively simple matter to remove the entire unit 24, after which the broken shear pin is replaced and the unit re-installed in the rotor. The knock-out pin 36 can likewise be readily replaced to restore the machine to normal operating condition.

I claim:

In high speed centrifuge apparatus, a horizontal mounting wall, a vertical drive shaft having an upper end portion extending through said wall and adapted for coupling to a rotor, a centrifuge rotor adapted to carry samples to be centrifuged and adapted to be removably socketed upon the upper end portion of the shaft whereby the rotor is driven when the shaft is rotated, the rotor having a lower annular portion, a fitting mounted in said annular portion, a weighted pin slidably carried by the fitting and movable between generally radially extended and retracted limiting positions relative to the outer peripheral surface of said annular portion, said pin when in extended position projecting beyond the contour of said outer periphery, a shear pin serving to normally lock said first named pin to said fitting and in retracted position said shear pin being broken by centrifugal force acting upon said first named pin when the speed of rotation of the rotor exceeds a predetermined value, driving means for the shaft including an electrical circuit adapted to be opened to reduce application of driving torque to the shaft, and a knock-out electrical conductor included in series with said circuit and mounted on said wall in spaced proximity with the outer periphery of said annular portion when the rotor is seated upon the shaft, said weighted pin serving to knock out said conductor when in its extended position.

EDWARD G. PICKELS.
